COVER FOR PRIMARY CHAIN FOR MOTORCYCLE

Larry L. Ziegler, 1918 5th St.,
San Fernando, Calif. 91340

Filed Jan. 14, 1972, Ser. No. 218,048

Term of patent 14 years

Int. Cl. D12—11

U.S. Cl. D90—5

Fig. 1.

Fig. 2.

Fig. 5.

Fig. 3.

Fig. 6.

Fig. 4.

FIG. 1 is a perspective view of a cover for primary chain for motorcycle showing my new design; it being understood that the broken line showing of the motorcycle is for illustrative purposes only;

FIG. 2 is a front elevational view thereof on an enlarged scale;

FIG. 3 is a bottom plan view thereof taken on line 3—3 of FIG. 2 on an enlarged scale;

FIG. 4 is a rear elevational view thereof taken on line 4—4 of FIG. 3 on an enlarged scale;

FIG. 5 is an end elevational view thereof taken on line 5—5 of FIG. 2 on an enlarged scale; and

FIG. 6 is an end elevational view thereof taken on line 6—6 of FIG. 3 on an enlarged scale.

I claim:

The ornamental design for a cover for primary chain for motorcycle, substantially as shown and described.
